DESIGN FOR A LIP STICK HOLDER

Herbert H. Harris, New York, N. Y.

Application July 21, 1933. Serial No. 48,786

Term of patent 14 years

To all whom it may concern:

Be it known that I, HERBERT H. HARRIS, a citizen of the United States and resident of New York city, in the county and State of New York, have invented a new, original, and ornamental Design for Lip Stick Holder, of which the following is a specification, reference being had to the accompanying drawing, forming part thereof.

The figure is a perspective view of a lip stick holder showing my new design.

The essential features of my design consist in a holder for a lip stick which includes a cylindrical

body having raised annular surfaces at each end defining end bands, between which is a peripheral surface having areas of a color contrasting with the color of the end bands and which areas are so arranged that the edges thereof define a zig-zag ornamental line with circular elements at the apices thereof.

I claim:

The ornamental design for a lip stick holder, substantially as shown and described.

HERBERT H. HARRIS.
